UNITED STATES PATENT OFFICE.

STEPHEN DENEGA, OF HUBBARD, SASKATCHEWAN, CANADA.

GRAIN-CAR DOOR.

Application filed February 28, 1927. Serial No. 171,638.

This invention relates to certain new and useful improvements in grain car doors and has for its primary object to provide a grain car door formed of independent panels or sections disposed one above the other and 5 slidable in guideways at the door opening with devices for raising and lowering the several sections of the door.

A further object of the invention is to 10 provide a grain car door of the above type wherein a box or casing disposed beneath the car bottom and at the side of the car in proximity of the door opening for receiving the lowered door sections that are laterally 15 displaced into the box to permit lowering movement of the next above door section with the several door sections when shifted to open positions and disposed within the receiving box having spring devices associated therewith for normally forcing the 20 same to a position to be operatively engaged by the operating devices for raising and lowering the several door sections.

With the above and other objects in view 25 that will become apparent as the nature of the invention is better understood, the same consists in the novel form, combination and arrangement of parts hereinafter more fully described, shown in the accompanying drawings and claimed.

In the drawings wherein like reference characters indicate corresponding parts throughout the several views,

Figure 1 is a side elevational view of a 35 grain car equipped with the door that constitutes the present invention;

Figure 2 is a front elevational view, partly broken away of one of the panels or sections of the door showing the anti-friction 40 guide rollers at one end and the rack teeth at the other end;

Figure 3 is a longitudinal horizontal sectional view taken on line 3—3 of Figure 1, showing the panel guides at each side of the 45 door opening for the several door sections and the gear wheel operatively engaged with the rack teeth at one end of one of the door sections;

Figure 4 is a vertical cross sectional view 50 taken on line 4—4 of Figure 1 showing the three sections of the door in their raised closed position, and the tensioned latch bar for holding the door sections closed and locked, there being also shown the box beneath the car bottom for receiving the several sections of the door;

Figures 5 and 6 are vertical sectional views, similar to Figure 4 showing the several door sections received in the box beneath the car door opening; 60

Figure 7 is a detail sectional view taken on line 7—7 of Figure 1 showing the slotted guide in the end wall of the box with the end of the latch bar extending therethrough; and

Figure 8 is a detail sectional view taken on 65 line 8—8 of Figure 1 showing the key releasable latch carried by the latch bar that is engaged with the lower edge of the lower section of the door for holding the several sections of the door in their closed and 70 locked position.

Referring more in detail to the accompanying drawing, there is illustrated by the reference numeral 1, a grain car having a side door opening 2 that is closed by a door 75 comprising side edge engaging vertically sliding sections 3, 4 and 5.

As shown in Figure 3, the door opening 2 is provided on its opposite vertical sides at the outer side of the car body with angle 80 iron guides 6 and 7 between which the sections of the door vertically slide. The several door sections are of identical construction and as shown in detail in Figure 2, one vertical side edge of the door section has 85 anti-friction guide rollers 8 journaled in bracketed portions of said edge while the opposite side edge of the door section is provided with rack teeth 9. With the door sections 3, 4 and 5 disposed in the angle iron 90 guides 6 and 7, the anti-friction rollers 8 move over the guide 6 while the rack teeth 9 upon the opposite corresponding ends of the several door sections move in proximity of the angle guide 7. 95

The several door sections are successively lowered into a receiving casing or box disposed beneath the car bottom adjacent the side door opening 2 and to effect raising and lowering movement of the several door sections in the guides 6 and 7, there is provided a toothed wheel 10 journaled in the bearing 11 at one side of the door opening 2 with the peripheral edge of the toothed wheel 10 extending through an opening in the angle 100 guide 7 for engagement with the rack teeth 9 upon the several door sections, the wheel 10 being provided with a handle 12 for rotation thereof. 105

The box disposed beneath the car door 110 opening for receiving the several door sections is open at its front side as shown in

Figures 1 and 4 and comprises a bottom wall 13, a rear wall 14 and end walls 15, the box being secured to the car beneath the floor 16 thereof in any preferred manner. A rod 17 horizontally disposed and slidable through a bearing carried by the rear wall 14 is disposed adjacent each of the four corners of the rear wall and carries an enlarged head 18 at the inner end thereof within the box, a coiled spring 19 surrounding each rod between the head 18 and rear wall 14 of the box.

When the several doors, 3, 4 and 5 are in their elevated and closed positions as shown in Figure 4, the latch bar 20 is disposed beneath the lower edge of the lower door section 3 to prevent lowering movement of the several door sections. The latch bar 20 carries a reduced tongue 21 at each end thereof that extends through the slot 22 formed in the end walls 15 of the box and form guides for sliding movement of the latch bar. A rod 23 is carried by the latch bar and extends through a bearing in the rear wall 14 of the box, the latch bar 20 being normally influenced in the direction toward the forward open side of the box and to assume a position beneath the door sections by the spring 24 surrounding the rod 23 between the latch bar 20 and rear wall of the casing. As shown in Figure 8, a key operated latch mechanism 25 is carried by the latch bar for locking engagement with a keeper socket in the lower edge of the lower door section 3.

When the several door sections 3, 4 and 5 are in their elevated and closed positions as shown in Figures 1 and 4, the spring 24 upon the rod 23 projects the latch bar 20 forwardly to be positioned beneath the lower door section 3 for latching engagement therewith as shown in Figure 8. When it is desired to open the door of the grain car, the latch mechanism 25 is released by a key and the latch bar 20 is manually forced rearwardly against the tension of the spring 24. The toothed wheel 10 is then rotated and being in engagement with the rack teeth 9 upon the lower door section 3, said door section is lowered into the box beneath the car opening and occupies the position forwardly of the tensioned plungers 17. This position of the door sections is shown in Figure 5. When the several door sections are completely removed from the door opening 2, they are disposed in the receiving box as illustrated in Figure 6. When the door sections are in the position shown in Figure 5, the lowered door section 3 is manually forced rearwardly toward the rear wall 14 of the box and against the tension of the springs 19 to provide clearance for the lowering movement of the next upper door section 4 that is lowered by the toothed wheel 10 meshing with the rack teeth 9 upon the adja-

cent end of the door section 4. When the door section 4 has been lowered into the box, both of the door sections 4 and 3 are then further moved toward the rear wall of the box to provide a clearance for the lowering movement of the upper door section 5 and when the three door sections have been lowered into the box as shown in Figure 6, the latch bar 20 is automatically projected forwardly under the influence of the spring 24. The toothed wheel 10 is so disposed with reference to the box that the rack teeth 9 at the upper end of each door section are in meshing engagement with the toothed wheel when the door sections are completely lowered into the box, the door sections being displaceable from the toothed wheel by rearwardly sliding movement thereof into the box toward the rear wall thereof. It will therefore be seen that the toothed wheel 10 remains in meshing engagement with the rack teeth upon the door section that is at the outer open side of the box.

In closing the door opening 2, the latch bar 20 is pushed rearwardly against the tension of the spring 24 to remove the same from the upper path of movement of the upper door section 5, the toothed wheel 10 is then rotated for raising the door section 5, and at the proper moment, the springs 19 will forwardly project the two remaining door sections 3 and 4 to position the door section 4 to be engaged by the toothed wheel 10 and when the three door sections have been raised into the door opening 2, the latch bar 20 is automatically projected by the spring 24 and the several door sections are then locked in their closed position.

From the above detailed description of the invention, it is believed that the construction and operation thereof will at once be apparent, and while there is herein shown the preferred embodiment of the invention, it is nevertheless to be understood that minor changes may be made therein without departing from the spirit and scope of the invention as claimed.

What I claim as new is:

1. In a grain car door, a door formed of a plurality of vertically sliding sections, means for raising and lowering the sections, and a box disposed beneath the door opening for successive reception of the door sections during lowering movement, slidably tensioned rods carried by the rear wall of the box and disposed for engagement with the door sections for normally moving the door sections toward the outer side of the box and in alignment with the car door opening.

2. In a grain car door, a door formed of a plurality of vertically sliding sections, means for raising and lowering the sections, a box disposed beneath the door opening for successive reception of the door sections during lowering movement, the raising and lower-

ing means comprising rack teeth on corresponding ends of the door sections, and a toothed wheel positioned for meshing engagement with the rack teeth, slideable tensioned rods carried by the rear wall of the box and disposed for engagement with the door sections for normally moving the door sections toward the outer side of the box and in alignment with the car door opening.

10 3. In a grain car door, a door formed of a plurality of vertically sliding sections, means for raising and lowering the sections, a box disposed beneath the door opening for successive reception of the door sections 15 during lowering movement, and a tensioned latch bar horizontally slideable at the upper end of the box to be positioned beneath the lower door section and latched thereto for holding the door sections in closed positions, 20 slideable tensioned rods carried by the rear wall of the box and disposed for engagement with the door sections for normally moving the door sections toward the outer side of

the box and in alignment with the car door opening.

4. In a grain car door, a door formed of a plurality of vertically sliding sections, means for raising and lowering the sections, a box disposed beneath the door opening for successive reception of the door sections during lowering movement, the raising and lowering means comprising rack teeth on corresponding ends of the door sections and a toothed wheel positioned for meshing engagement with the rack teeth, a tensioned 35 latch bar horizontally slideable at the upper end of the box to be positioned beneath the lower door section for holding the door sections in closed positions, slideable tensioned rods carried by the rear wall of the box and 40 disposed for engagement with the door sections for normally moving the door sections toward the outer side of the box and in alignment with the car door opening.

In testimony whereof I affix my signature.

STEPHEN DENEKA.
